UNITED STATES PATENT OFFICE.

WILLIAM G. PRICE, OF NEW CASTLE, PENNSYLVANIA.

TRUCK.

No. 872,017.

Specification of Letters Patent.

Patented Nov. 26, 1907.

Application filed January 17, 1907. Serial No. 352,710.

To all whom it may concern:

Be it known that I, WILLIAM G. PRICE, a resident of New Castle, in the county of Lawrence and State of Pennsylvania, have 5 invented a new and useful Improvement in Trucks; and I do hereby declare the following to be a full, clear, and exact description thereof.

My invention relates to trucks and more 10 especially to motor trucks.

The objects of my invention are to provide for the strengthening and stiffening of the frame of the truck so as to furnish a very rigid and durable construction which will 15 withstand the severe strains and shocks to which said trucks are subjected.

To these ends my invention comprises the novel features hereinafter set forth and claimed.

20 In the accompanying drawings Figure 1 is a plan view of one-half of my improved truck, it not being deemed necessary to illustrate the other half which is an exact duplicate; Fig. 2 is a side elevation partly 25 in section; Fig. 3 is a detail section on the line 3—3, Fig. 1; Fig. 4 is a view of the inner pedestal; Fig. 5 is a modified form of gusset plate.

The numeral 2 designates the axles carrying 30 the wheels 3, said axles being journaled in suitable journal boxes 4 in the ordinary manner. The bolster 5 illustrated is of a common type and as it forms no part of my present invention I will not describe 35 the same in detail. This bolster is provided with ordinary center bearing plates 5^a and suitable springs 7 are employed.

The truck illustrated and to which my invention is applicable has certain features 40 which form the subject matter for an application for Letters Patent of the United States filed by me August 18, 1906, No. 331,139. Accordingly, said structure has the transoms 6 which may be formed of angle 45 bars of suitable dimensions. The extreme ends of said transoms are bent to form the right angle portion 6^a by means of which the transoms are secured by rivets 8 to the side frames 9. The bolster hanger brackets 10 have the inwardly bent portions 11 through 50 which the rivets 12 pass which secure said brackets to the side frames 9. The opposite ends of the hanger brackets 10 are secured by the rivets 13 to the transoms 6.

55 The side frame stiffener plate 14 is riveted

to the side frame 9 by rivets 8 and 15, said stiffener plate projecting above the side frames 9 and also slightly below the same, and said stiffener plate being secured to the outer face of said side plate. The purpose 60 of this stiffener plate is to resist bending and not compression of the side frame. Gusset plates 16 are secured by the rivets 17 to the transom 6 and said gusset plates have the flanges 18 which are riveted by rivets 65 19 to the upper portion of the stiffener plate 14. This provides a very strong and rigid connection between the transoms and the side plates. By having the gusset plate secured to the stiffener plate on the outside 70 of the side frames the parts are so united as to form a very strong structure.

The side frames 9 are formed of a single piece of metal bent to the desired shape. Secured to the side frames are the pedestals 75 20 and 21. The inner pedestal 20 may be formed of a single piece of metal and is secured by the rivets 22 to the side frame. This pedestal 20 fits into the groove 23 formed by the lugs 24 on the journal boxes 80 4. The outer pedestal 21 fits in a like seat or groove 26 in that side of the journal box 4. The pedestals 20 and 21 are connected at the bottom by the bolt 27 with the spreader 28 interposed between said pedestals. By this construction I obviate the necessity of securing the journal box to the equalizing bar 29 as has ordinarily heretofore been the construction adopted.

The pedestals 20 and 21 may be pressed 90 to shape of metal of suitable thickness.

In Fig. 5 I have shown a modified form of gusset plate in which but a single piece of metal is employed instead of employing two separate gusset plates, as in the first instance.

What I claim is:

1. In a truck, the combination of side frames, a bolster, transoms secured to said side frames, a stiffener plate on the outside 100 of said side frame, and gusset plates connecting said transoms to said stiffener plate.

2. In a truck, the combination of side frames, a bolster, transoms secured to said side frames, a stiffener plate secured to the 105 outer face of said side frames, said stiffener plate projecting above said side frames, and gusset plates secured to said transoms and to the upper portion of said stiffener plate.

3. In a truck, the combination of side 110

frames, a bolster, transoms secured to said side frames, a stiffener plate secured to the outer faces of said side frames, said stiffener plate extending above and below said side frames, and gusset plates secured to said transoms and to the upper portion of said stiffener plate.

In testimony whereof, I the said WILLIAM G. PRICE, have hereunto set my hand.

WILLIAM G. PRICE.
